GUN MOUNT, MORE ESPECIALLY FOR USE IN
AIRCRAFT

Alfred Funk, Dessau, Germany, assignor to Junkers Flugzeug-und-Motorenwerke Aktiengesellschaft, Dessau, Germany

Application April 19, 1938, Serial No. 202,936
In Germany April 30, 1937

5 Claims. (CL 89—37.5)

This invention relates to gun mounts, and refers particularly to gun mounts for use in aircraft. It aims, among other things, to provide means for mounting a gun in aircraft in such a manner as to afford maximum accuracy and range.

It is well known to those skilled in the art that guns, when in firing position, must always be so positioned that both the axis of the barrel and the sight line lie in one vertical plane. This is because the projectile, on leaving the barrel, is subject to gravity attraction and when mounting the sighting device on the gun the deflection of the projectile, caused by gravity action, must be taken into consideration. Therefore the sighting line is disposed at an angle to the axis of the barrel. This angle depends upon the distance of the target to be sighted and must correspond to the curve described by the projectile, which must intersect the sighting line at the target. Since deflection of the projectile by gravity always occurs in a vertical direction, it is assumed when mounting the sighting device that, when fired, the gun is always so held that the axis of its barrel and the sighting line lie in the same vertical plane. If the gun, when in firing position, is not so held that the axis of the barrel and the sighting line lie in the same vertical plane, for instance, if the gun is tipped, the conditions taken into consideration when mounting the device on the gun no longer exist, and accuracy of aim can no longer be depended on. If the gun is held by a carrier member which is not fixed in position, or if, when this carrier member changes its position, the gun is tipped, means must be provided to enable the gunner to adjust the gun to a position necessary for obtaining accuracy. Therefore when mounting guns on vehicles they have been so supported for rotation that it is possible, at all positions of the vehicle, to adjust the gun so that the axis of the barrel and the sighting line lie in one vertical plane.

Provision must further be made so that in no position which the gun may assume relative to its carrier member is the gunner's visibility obstructed; that is, the sighting line should not be obstructed by nontransparent parts. The present invention contemplates a solution of this problem by providing a support for a gun traversing a panel, in which the gun can be adjusted at all times to correct position relative to the sight and in which an unobstructed view is obtained along the sighting line in all possible positions of the gun relative to the panel.

In this invention the gun traverses a pane or panel which constitutes the carrier member for the gun and is sufficiently strong, consisting for instance of a thick glass pane or artificial resin plate, to transmit the forces created by the gun.

The latter is supported for rotation about an axis

extending through the panel, at least an annular portion of which is transparent and the center of which coincides with the axis of rotation of the gun. The mean radius of the panel must equal the distance between the points at which the sighting line and the axis of rotation extend through the panel. When the vehicle turns about an axis which is substantially parallel to the axis of rotation of the gun the latter can always be properly adjusted relative to the sight without interfering with visibility along the sighting line.

If the gun is supported relative to the panel for rotation about its own axis, and also for rocking movement in any desired plane, for instance by means of a ball or a Cardan Joint, then during the rotary and oscillating movements of the gun relative to the panel the point at which the sighting line traverses the panel lies in an annular path. Therefore the panel must at least be transparent in this annular portion of its total area and the required minimum width of the transparent panel portion must correspond to the largest possible angle through which the gun may be oscillated relative to the panel, and to the distance between the sighting line and the axis of rotation.

If the gun is arranged on a vehicle, and more especially on an aircraft, it is advisable to prevent the relative wind from hindering the gunner handling it and also to render its range of fire greater than is possible by merely supporting it for rotation and oscillation in the panel. To this end it is advantageous to support the gun in the panel for oscillation and rotation and to arrange the panel for displacement in a meridian slot of a cupola which can be rotated relative to the craft. By rotating the cupola the meridian slot can be adjusted in any desired direction radially to the axis of rotation of the cupola. The panel carrying the gun can be shifted along the slot and the gun itself can be oscillated relative to the panel whereby an extended range of fire, which under favorable circumstances exceeds 180 degrees, is obtainable. When the cupola is turned and the panel moved the gun is correctly positioned relative to the sighting device. Relative movement occurs between the gun and the panel during which, however, the sighting line can never extend through non-transparent parts and so visibility is not hindered.

In the drawings affixed to this specification and forming part thereof an embodiment of my invention is illustrated diagrammatically:

In the drawings:

Figure 1 is a section on the line 1—1 of Figure 2 along the axis of a cupola in the meridian slot of which the panel forming the carrier member for the gun is arranged for displacement.

Figure 2 is a section on the line II—II of Figure 1.

Figure 3 is an end view of the panel carrying the gun.

5 Figure 4 is a cross section of the gunner's stand arranged at the front of an aircraft, and

Figures 5 to 8 illustrate perspective views of four different relative positions of the gun, the panel, and the cupola.

10 Referring to the drawings, 1 is the gun and 2 is a bearing having a partly spherical outer surface and serving to support the gun like a ball joint, for oscillation in the bearing body 3 fixed to the vaulted panel or pane 5. This panel is 15 mounted in a frame which is arranged for displacement in a meridian slot 12 of a cupola 13 which is supported by an antifriction bearing 25 for rotation on an aircraft body or fuselage 26. To the frame 4 of the panel 5 carrying the gun 1 are fixed arms 14 which can be turned about 20 bolts 15 mounted in the cupola 13. The bolts 15 are so arranged that their common axis extends through the center of the cupola and at right angles to meridian slot 12. If the panel 5 is to 25 be moved in the meridian slot a bowed handle 16 connected to the arms 14 is rocked about the bolts 15. If the cupola is also to be rotated the handle 16 is rocked about the axis of rotation of the said cupola.

30 In order to secure the panel 5 and the cupola 13 in different positions to which the gun may be adjusted a locking device operable by means of an auxiliary handle 22 is provided. Movement of the latter is transmitted by means of 35 Bowden cables 21 and 28 to spring urged locking pins 20 and 27 provided in the frame 4 and cupola 13 respectively, to engage notches 18 in an edge 17 of the meridian slot and notches 9 in the fuselage 26. By pressing the two handles 16 and 40 22 together the locking pins 20 and 27 are withdrawn from their notches so that the cupola 13 and the panel 5 can be rotated and moved respectively.

In order to guard the gunner against the relative wind the frame 4 includes, besides the panel 5 carrying the gun, covering panels 23 and 24 which are located on each side of the panel 5 in the direction of the meridian line and which, with the panel 5, cover the greater part of the 50 length of the meridian slot. The covering panels 24 are so staggered relative to the panels 23 that in one position they extend into the interior of the cupola 13.

55 When aiming the gun at a target, the cupola 13 is first so rotated that the center of the meridian slot extends approximately through the target. Then the panel 5 is so moved in the slot that the gun points approximately at the target, and finally the gun is so oscillated relative to 60 the panel that the sighting line, that is, the line which connects the bead 30 with the center of the sight 31, points exactly towards the target.

When adjusting the gun it is held in such a 65 position that the sighting line and the axis of the barrel extend in one vertical plane. Therefore, when the cupola 13 is rotated, the gun is rotated relative to the panel 5. Visibility for the gunner cannot be obstructed because the panel 5 is transparent at all annular portions surrounding the bearing 3 for such width that at all positions of the cupola 13, frame 4 and gun 1, the sighting line x—x extends through this transparent portion (see Figures 3 and 5 to 8) and is not obstructed by non-transparent parts. The

width of the transparent annular portion of the panel 5 corresponds to the angle of oscillation through which the gun can be rocked and to the distance between the sighting line x—x and the axis of the barrel of the gun, which also constitutes the axis of rotation of the said gun.

I wish it to be understood that I do not desire to be limited to the exact details of construction shown and described for obvious modifications will occur to one skilled in the art.

What I claim is:

1. An aircraft gun mount comprising, in combination with an aircraft body having a wall with an opening therein, a slotted curved shell adapted to cover said opening, means positioning said shell over the opening for rotation about an axis intersecting the plane of said opening, supporting means rigid with said shell positioned inside the same, a frame member of substantially the contour of said shell and having an opening therein, means extending from the frame and pivotally connected with said supporting means for swinging the frame, a transparent panel positioned within the opening in said frame, a gun extending through said panel and said slot, and gun supporting means carried by the panel constructed and arranged to support the gun for rotary movement about its longitudinal axis.

2. An aircraft gun mount comprising, in combination with an aircraft body having a wall with an opening therein, a slotted curved shell adapted to cover said opening, means positioning said shell over the opening for rotation about an axis intersecting the plane of said opening, supporting means rigid with said shell positioned inside the same, a frame member of substantially the contour of said shell and having an opening therein, means extending from the frame and pivotally connected with said supporting means for swinging the frame, a transparent panel fixedly positioned within the opening in said frame, a gun extending through said panel and said slot, and gun supporting means carried by the panel constructed and arranged to support the gun for rotary movement about its longitudinal axis.

3. An aircraft gun mount comprising, in combination with an aircraft body having a wall with an opening therein, a slotted curved shell adapted to cover said opening, means positioning said shell over the opening for rotation about an axis intersecting the plane of said opening, supporting means rigid with said shell positioned inside the same, a frame member of substantially the contour of said shell and having an opening therein, means extending from the frame and pivotally connected with said supporting means for swinging the frame, a transparent panel fixedly positioned within the opening in said frame, a gun extending through said panel and said slot, and gun supporting means carried by the panel constructed and arranged to support the gun for universal pivotal movement about a point lying substantially within the surface of the panel and for rotary movement about its longitudinal axis.

4. The arrangement of claim 3 wherein the gun supporting means carried by the panel consists of a ball joint.

5. The arrangement of claim 3 wherein the frame is provided with other openings around the aforesaid opening, a panel in each of said openings, and the gun supporting means is carried by the panel in the aforesaid opening.

ALFRED FUNK,
